(57) **CLAIM**

The ornamental design for “fence bracket for a potted plant,” as shown and described.

DESCRIPTION

FIG. 1 is a front view of my new “fence bracket for a potted plant”

FIG. 2 is a right side view of my new “fence bracket for a potted plant” the left side view being a mirror image thereof.

FIG. 3 is a backside view of my new “fence bracket for a potted plant”

FIG. 4 is a top view of my new “fence bracket for a potted plant”; and,

FIG. 5 is a bottom view of my new “fence bracket for a potted plant”.

My bracket is characterized by a novel shape and is used for removably attaching a potted plant onto a fence.
